UNITED STATES PATENT OFFICE.

JAMES M. HOPKINS, OF CHICAGO, ILLINOIS.

SLIDING-DOOR FASTENER.

1,071,745.

Specification of Letters Patent. Patented Sept. 2, 1913.

Application filed October 28, 1912. Serial No. 728,193.

To all whom it may concern:
Be it known that I, JAMES M. HOPKINS, a citizen of the United States, and a resident of the city of Chicago, county of Cook, and State of Illinois, have invented certain new and useful Improvements in Sliding-Door Fasteners, of which I do declare the following to be a full, clear, and exact description, reference being had to the accompanying drawing, forming part of this specification.

Figure 1 is a view in side elevation of part of the side wall of a railway car having my invention applied thereto. Fig. 2 is an enlarged detail view in cross section on line 2-2 of Fig. 1. Fig. 3 is a view in section on line 3-3 of Fig. 4. Fig. 4 is a detail face view of the stop brace. Fig. 5 is a front end view of the stop brace shown in Fig. 4.

A designates the door post at the left-hand side of the doorway, that is formed in the car wall. To this door post is connected a stop bar B that consists of a metal angle bar, the base flange of which abuts against and is securely connected to the post A by means of through bolts. Against the outstanding flange of the stop bar B the left-hand edge of the door C will contact as the door is closed.

Against the outstanding flange of the stop bar B bears a brace E of novel construction. This brace is preferably formed as a malleable casting and, as shown, comprises an inner member e that is connected by a through bolt e' to the side wall of the car. The inner member of the brace E is recessed (see Fig. 2) where it sets over the inner flange of the stop B, and is formed with an outstanding portion e² that bears against the outstanding flange of the stop B. The brace E is formed with a ledge or outer portion e⁴ that carries the eye or staple e⁵ (preferably formed integral therewith) that will be engaged by the hasp F that is attached to the door C by a staple F'. As shown, the brace E is formed at its top with an offset portion e⁶ having a headed pin e⁷ passing through the elongated slot g of the bolt G. The brace E is formed with lips or flanges e⁸ adapted to project over the edge of the door C and preferably, also, with integral webs e¹⁰ whereby the brace is strengthened.

From the foregoing description it will be seen that when the door is closed the hasp F

will be turned, so that its free end will pass over the eye or staple e⁵, after which the bolt G will be dropped so as to pass through the eye or staple e⁵ and hold the hasp F 60 in engagement therewith. The lower end of the bolt G will be provided, of course, with the usual hole therethrough to admit the wire of the car seal.

The brace E not only affords a most effective means for bracing the stop bar B, but also affords a means for supporting the bolt G and the eye or staple e⁵ whereby the free end of the hasp F is engaged.

Having thus described my invention, 70 what I claim as new, and desire to secure by Letters Patent, is:

1. In a railway car, the combination with the post at the front edge of the door opening, of a door stop comprising an angle bar 75 extending lengthwise of said post and having a base flange abutting against and secured thereto and an outstanding flange against which the front edge of the door abuts, and a separate brace abutting against 80 and secured to the side of the car and having a portion abutting against the outstanding flange of said angle bar, said brace having a ledge adapted to carry one end of the lock mechanism and having a portion 85 overlapping the outstanding flange of the stop bar and adapted to resist the outward movement of the door.

2. In a railway car, the combination with a post at the front edge of the door opening, of a door stop comprising an angle bar 90 extending lengthwise of said post and having a base flange abutting against and secured thereto and an outstanding flange against which the forward edge of the door 95 abuts, and a separate cast metal brace for said door stop having a base portion abutting against and secured to the side of the car and extending over the base flange of said angle bar, said brace having a portion of abutting against the outstanding flange of said angle bar and a ledge formed integral therewith and provided with a staple to engage the hasp of the door.

3. In a railway car, the combination with the post at the front edge of the door opening, of a stop comprising an angle bar extending lengthwise of the door and having a base flange abutting against and secured to the post and an outstanding flange against 110 which the front edge of the door abuts, and a separate cast metal bracing shoe for said

angle bar having a base portion abutting against and secured to the side of the car and extending over the base flange of said angle bar, said bracing shoe having an outstanding portion abutting against the outstanding flange of said angle bar and provided with a flange overlapping the outer edge of said angle bar and arranged to engage the forward edge of the door, and

said bracing shoe having a ledge and an offset formed integral therewith, and a bolt mounted on said offset, said ledge having an eye for receiving said bolt.

JAMES M. HOPKINS.
